FIG. 10

FIG. 1 is a plan view of a combined park, turn signal and side marker light embodying our new design;

FIG. 2 is a rear elevational view thereof, the front elevation being a mirror image thereof;

FIG. 3 is a bottom plan view thereof;

FIGS. 4 and 5 are, respectively, left and right hand side elevational views thereof;

FIG. 6 is a plan view of a modified form of the light disclosed in FIG. 1;

FIG. 7 is a rear elevational view thereof, the front elevation being a mirror image thereof;

FIG. 8 is a bottom plan view thereof; and

FIGS. 9 and 10 are, respectively, left and right hand side elevational views thereof.

The prismatic pattern on the side reflectors in FIGS. 4 and 9 is partially shown for convenience of illustration.

This is a continuation-in-part of design application Ser. No. D. 13,186 filed Aug. 19, 1968 and now abandoned.

We claim:

The ornamental design for a combined park, turn signal and side marker light, as shown and described.
